EARL H. WADSWORTH INVENTOR.

BY Louis Untermeyer

ATTORNEY:

UNITED STATES PATENT OFFICE.

EARL H. WADSWORTH, OF CORTLAND, NEW YORK, ASSIGNOR TO THE BREWER-TITCHENER CORPORATION, OF CORTLAND, NEW YORK, A CORPORATION OF NEW YORK.

NONCOLLAPSIBLE VEHICLE TOP.

Application filed February 7, 1924. Serial No. 691,201.

To all whom it may concern:

Be it known that I, EARL H. WADSWORTH, a citizen of the United States, and a resident of Cortland, in the county of Cortland and the State of New York, have invented certain new and useful Improvements in Noncollapsible Vehicle Tops, of which the following is a specification.

My invention relates to a novel light but exceptionally rigid frame structure for vehicle tops, and pertains particularly to non-collapsible or so-called permanent open tops having removable side curtains or window panels adapted to conveniently change the open top into an enclosed winter top structure for the vehicle body,

A feature of the present frame structure resides in an improved construction for the pair of complementary side rails therefor, and in the type of fastening joints provided for bridging these rails with transverse bows. A further important feature lies in the use of a metal jamb strip running lengthwise of and overlapping the lower inner face of the complementary side rails to constitute an abutting strip against which to set the upper edge of the window panel. Furthermore, certain portions of such continuous jamb strips are offset from the rail face to form a series of spaced sockets, or stake pockets, adapted to receive the bow clips that extend beyond the leg ends of my transverse bows.

Each of my side rails is preferably made up in sections of substantially similar cross sectional profile that abut end to end, and these sections are suitably attached to a continuous jamb strip, which strip also serves as a connecting member for the adjacent rail ends. The side rails, as well as the transverse bows which bridge the rails, are made of tubular form adapted to metal encase wood filler blocks. Each filler block is exposed through a longitudinal slot in the metal sheath and this allows of tacking the deck fabric to any part of the top frame structure.

It is the further object of this invention to incorporate improved bracing means for tying the associated top parts together. Suitable means have also been devised for readily and cheaply assembling the top parts on the vehicle body, and for compactly storing and shipping the unassembled top parts while in transit.

Embodying herein are also other features of structure and arrangement of parts designed to facilitate the economical manufacture of permanent tops and their application to vehicle bodies, all of which will be set forth in detail hereinafter.

Reference is had to the accompanying two sheets of drawings which illustrate an example of the preferred form of my invention, like characters of reference indicate like parts in the several views, and in which drawing:

Fig. 1 represents an elevational view taken in section lengthwise of my top structure and showing its points of attachment to a vehicle body.

Fig. 1a, shows a detail of a link method of fastening the lower end of the main bow standard to the pivot iron.

Fig. 1b, is a sectional view of this detail as taken along the line 1a—1b of Fig. 1a.

Fig. 2, shows a half plan or bottom view of Fig. 1 as seen from the underside of the deck fabric.

Fig. 3, illustrates the constructive details of a transverse bow and its assemblage with the supporting side rail structure as taken along the line 3—3 of Fig. 1.

Fig. 4, is a similar view of said transverse bow partially contracted, as taken along line 4—4 of Fig. 1.

Fig. 5, is an enlarged cross-sectional view of the side rail and the jamb strip also taken along line 4—4 of Fig. 1, showing details of the deck fabric trim and the method of abutting the window panel against said strip.

Fig. 6, represents a perspective view illustrating the clip fastening device used to tie the leg of the intermediate transverse bows to one of its supporting side rails.

Fig. 7, shows in perspective some further details of the bow receiving socket for mounting the rear bow; also the bracket plate for pivotally securing the upper end of the standard to the side rail structure.

Fig. 8, is a cross-sectional view of the transverse bow as taken on line 8—8 of Fig. 3.

The illustrative embodiment of my invention comprises a pair of main bow standards such as 1, having their respective lower ends mounted upon a pivot iron such as 2, which iron is secured to each side of the vehicle body 3 in the conventional manner.

As shown in Figs. 1_a and 1_b, the lower fulcrumed end portion of the standard 1 is provided with a projecting flat link strap 1_c having a hole 1_d therein adapted to engage the pivot iron fulcrum while the shank portion 1_f of said strap extends back into the end of the metal casing of the main bow and is riveted thereto by means of the rivets 1_g. As shown, the filler block 9 which is mounted 5 within said casing is suitably recessed to admit of receiving the link shank 1_f. In my top structure, the main bow standard, as well as the other frame members, are preferably made up of sheet metal tubular sheaths 10 which are crimped over the edges of a substantially rectangular or parallelogram shaped wood filler block designated as 9. These blocks are preferably exposed on one 15 of their sides through a longitudinal tacking slot 9_a in a manner that will be more fully disclosed hereinafter.

Each of said standards extends upward and rearward with respect to the horizontal top edge or body trim line 3_a and the upper free ends of the respective standards are each provided with a slotted bow receiving socket 6 adapted to connect said standards with the rear transverse bow 4. This bow is preferably made of wood and as shown in 20 Fig. 1, the cover or deck fabric 5 is stretched downward over the rounded edge of said bow 4 to align with the rear of the body tonneau 3.

As is indicated in Fig. 7, the upper end of each standard is further equipped with an angular bracket plate 7, the depending leg 7_a of which is fastened to the standard by means of the rivets 7_d while the other leg 7_b is pivotally secured and locked to the rearward section of the side rail 8_a, all of which will be more fully explained hereinafter. The side rail and the standard are of substantially similar cross-sectional contour and it is pointed out that both these parts are mounted in alignment against the same 40 side of bracket plate 7.

The side rail member of my top structure is preferably, but not necessarily, formed of sheet metal in sectional lengths of substantially similar cross-sectional profile, and as shown in Figs. 1 and 2, three such sections, namely 8_a, 8_b and 8_c, are set end to end so as to align and constitute unitary side rail structure.

The particular cross-sectional shape of said metal rail lengths is immaterial for present purposes, but it is preferred to utilize a hollow or incomplete tubular profile for the rail sections, and particularly one of essentially crimped channel shaped contour such as is shown in detail in Fig. 5. As illustrated, the side rail is formed from a strip of sheet metal bent into a channel shape 60 about the rectangular wood filler block 9. The legs of the channel are made somewhat

longer than the side faces of the filler so as to allow the sheet metal to be crimped over the filler corners and snugly encase the filler in the manner of a sheath therefor, while at the same time providing for a longitudinal tacking slot 9_a between the inner edges of said crimped legs. This slot faces outwardly with respect to the center line of the complementary side rails and it will be apparent that said tacking slot is so disposed as to reduce the strength and rigidity of the rail section to an imperceptible extent.

The complementary side rails, each comprising the sections 8_a, 8_b and 8_c, extend forwardly from their respective standards and over the body 3 in a substantially horizontal plane with respect to the top edge or trim line 3_a. Each of these sectional rails is provided with a continuous jamb strip 10, to which said abutting sections are suitably fastened, preferably by means of rivets such as 10_a, extending through the rectangular side rail sections as is indicated in Fig. 5.

The longitudinal metal strip 10 is shown mounted along side of the inner or closed face of the incomplete rectangular rail tubes 8_a etc., that is to say opposite to the slot 9_a, of the filler sheath, and said strip is thus made to serve as a metallic tie means for the aligned rail sections. It will be observed that the width of the strip 10 is greater than the dimension of closed sheath wall against which it is riveted. The lower projecting edge 10_b depending from the side rail is intended to serve as an abutting face against which to mount the sash 18_a of the window panels 18.

As indicated in Figs. 1 and 2, the forward end of the side rails are bridged by means of the outrigger bow 11 which lies in alignment with the rail plane. The legs of said bow abut with the free end of the respective side rail sections 8_c and the pair of jamb strips 10 extend beyond this joint and are securely fastened to the said leg ends by means of the rivets 11_a. The outrigger bow is supported in the usual manner by means of the windshield stanchion 12.

The described side rail and jamb strip structure serves in the capacity of back bone for the top frame, and these rails are further bridged by a series of intermediate transverse bows designated as 13_a, 13_b and 13_c. As shown in Fig. 8, these bows are also metal sheathed and provided with a wood filler in a manner identical with that used for the side rail structure, and the tacking strip is likewise turned outward to face the deck fabric 5. An important feature of the present invention resides in the novel means provided for fastening the legs of the transverse bows to their respective side rails. For this purpose, the complementary jamb strips 10 are each offset from the inner rail face to form a series of spaced sockets or

stake pockets such as 14_a, 14_b and 14_c as shown in Fig. 2.

These pockets are integrally formed as flat shallow depressions or spaced troughs 5 in the jamb strip 10, and for convenience in manufacture, these troughs are all formed parallel to each other and preferably perpendicular to the longitudinal edge of said strip, as shown. As indicated in Fig. 6, 10 rivets such as 10_a are provided adjacent to each side of said trough for the purpose of securely tying same to the rail sheath at this point.

The bow clip 15 is attached to and extends 15 beyond each of the beveled ends of the transverse bow legs, which oblique ends are intended to rest and bear snugly against the flat top face of the side rails. This clip is provided with two parallel wings such as 20 15_b which serve to form a U-shaped sleeve partially surrounding the sides of the metal bow sheath, while the connecting web member of the clip wings is secured to the leg end of the transverse bow by means of rivets 25 such as 15_a. The clip is further provided with a depending male part 15_c which is neatly fitted into the stake pocket, such as 14_c and it will be observed that the center line of said depending male part is shifted 30 out of alignment with respect to the winged portion of the clip proper to an extent of the angle designated as α . By placing such angular displacement in the bow clip 15 structure, allows all the stake pockets 14_a, 35 14_b etc., to be formed perpendicular to the longitudinal side rail as described, while transverse bows may nevertheless be set at different angles thereto so as still to abut normally to the changing slope of the deck 40 line, as indicated in Fig. 1.

As shown in Figs. 5 and 6, the offset flat face of said stake pockets are further provided with a perforated lip part 14_e which serves as a groove means for engaging the 45 tongue 15_d formed in the depending male member 15_c. This tongue is intended to be of sufficient length to give it resiliency and is made somewhat narrower than the slot width of said lip part 14_e. The tongue 15_d is initially sprung out of alignment with respect to the face of the male part 15_c to permit said tongue end to snap beneath said 50 lip edge 14_e and snugly lock the transverse bow when the latter is set in place. The resilient tongue also serves to take up any excess lateral play in the socket fit and facilitates the economical assemblage of the frame structure. After the transverse bows are properly fitted in place, the clip 15 may be permanently secured into its stake pocket by means of rivets such as 10_a indicated in Fig. 5.

Referring in detail to the bow receiving 55 socket 6, as provided for the upper portion of the main standard, this is preferably

fashioned into a short sleeve section substantially identical in type of structure with slotted side rail sheath section shown in Fig. 7. The closed flat wall opposite the tacking slot of the socket 6 is secured to the bracket plate 7 by means of the rivets such as 6_a. The leg ends of the rear transverse bow 4 are then fitted into the pair of sockets such as 6 and suitably fastened therein so as to align with the standard 1 as indicated in Fig. 1.

A further constructive feature of this invention resides in the bracket plate 7 and the swivel method of fastening the standard 1 to the side rail and jamb strip, which method is adapted to collapse this portion of the top structure for the purpose of compactly stacking the demounted side rails in transport or storage. As shown in Fig. 7, the horizontal leg 7_b of said plate is provided with two spaced holes 7_c and 7_d. The latter is equipped with a fulcrum pin extending inwardly through the side rail and its adjacent jamb strip, while the hole 7_c is provided with a detachable bolt similarly extending through said parts. In the event that said bolt is removed, the free end of the standard may be swung about the fulcrum 7_d and made to lie alongside the rail 8_a in the manner indicated in Fig. 1 by dotted lines.

A further provision for locking the swivel joint and otherwise imparting increased stability and rigidity to the top structure when assembled upon the body, resides in the brace strap 16. This strap crosses the standard 1 and is pinned thereto by the fulcrum pin 16_a, while one of the strap ends is removably fastened to the rear side rail section 8_a by means of the pin 16_b. The other end of the strap is carried by a second pivot iron 2_a which is set in spaced relation from the similar main standard iron 2, as is best shown in Fig. 1. These parts may be sprung over their respective pivot 100 irons and locked in place. As further indicated in Fig. 1 by dotted lines, the brace strap 16 is also adapted to fold along side the rail 8_a, and align with the main standard 105 when it is desired to stack or store the unassembled top parts.

The brace straps impart proper longitudinal stability to the top structure without being dependent upon the windshield stanchions for such support. In addition, the various transverse bows are tied together by means of the strainer webs 17_a and also by the corner pad webs 17_b, both of which run lengthwise of the body from the outrigger bow to the rear bow, while the strainer webs extend downward and tie to the rear of the body tonneau 3. It will be seen therefore that the entire top frame is exceptionally well braced within itself and also with respect to the body, and that the 110 115 120 125 130

structure combines adequate longitudinal rigidity with the required inherent resiliency needed to properly absorb the inertia thrusts and other forces that may be due to road jolts or other causes.

The assembled frame parts are covered with a deck fabric 5 as indicated in the various views. By virtue the exposed tacking strip for the wood filler as provided throughout this top structure, said fabric may readily and cheaply be fastened to any of the frame parts as required. Fig. 5 shows in detail the preferred method of trimming the quarter deck fabric to the side rail. The fabric edge is undeturned and sewed, whereupon it is tacked along the side rail filler block at any desired pitch.

The improved mounting of the window panels is best indicated in Figs. 1 and 5. As explained, the side rail is preferably made to lie parallel to the plane of the top body edge or trim line 3_a. As shown in Fig. 2, the forward or windshield ends of the complementary side rails are bent inward toward each other so as to conform to the plan lines of the body contour. This dishing of the side rails allows the side window panels to be conveniently and neatly mounted between said parallel rails and the body trim line.

In addition to serving as tie means for the rail sections, the depending part 10_b of the jamb strip 10 further provides as an abutting face against which to mount the top edge of the window panels. As indicated in Fig. 1, these side panels are preferably fashioned into sectional door and window sashes such as 18_b, 18_c and 18_d, having end pieces 18_a and 18_f adapted to square up the adjacent sash edges thereof. The upper and lower edges of these panels may be secured in any convenient manner to the rail and body parts, respectively.

It will be obvious that the projecting strip part 10_b shown as depending from the inner face of the side rail is not essential and may be discarded in case when it is not desired to use any side panel enclosures for the body. It will further be understood that said side rails need not necessarily be made sectional as shown and that the longitudinal tacking slot 9_a need not necessarily be a continuous one since a plurality of slots placed at a suitable pitch may be made to serve the same purpose. Furthermore, the novel socket parts and other structural details generally may be subjected to modification without departing from the spirit and scope of my invention, heretofore described and more particularly pointed out in the appended claims.

Claims:

1. In a non-collapsible top structure for a vehicle body, a pair of main standards mounted upon opposite sides of the body,

an angular bracket plate for each of said standards, said plate having one of its legs secured to its respective standard, complementary side rails secured respectively to the other legs of said bracket plates, each set of standards and rails therefor being disposed upon the same side of the respective bracket plates, a jamb strip for each of the complementary rails said strip being respectively disposed on sides opposite to those stipulated for the bracket plates, separate fastening means extending through each of said rails and their respective adjacent strip and bracket leg members, a bow receiving socket secured to each bracket plate on the rail and standard side thereof, and a rear bow bridging said standards and having the legs thereof mounted in said pair of sockets.

2. In a non-collapsible top structure for a vehicle body, a pair of main standards mounted on opposite sides of the body, complementary side rails secured to the respective standards and extending forwardly therefrom over the body, a separate jamb strip for each of said side rails which strip is shaped to constitute a plurality of spaced offset stake pocket portions while the remaining intermediate spacing portions of the strip proper adjoin the side rail, and a transverse bow bridging the side rails provided with a bow clip extending beyond each of the respective leg ends of said bow and engaging certain of said stake pockets, said clips being disposed contiguous to the respective side rails and encompassed by their respective offset pocket portions of the jamb strips.

3. In a non-collapsible top structure adapted to mount a deck cover for a vehicle body, a pair of main standards mounted upon opposite sides of the body; complementary side rails secured to the respective standards and extending forwardly therefrom over the body in a substantially horizontal plane; a plurality of spaced transverse bows bridging the side rails, the respective leg ends of said bows being beveled and set substantially normal to the various slopes of the deck cover contour and at different angles with respect to the longitudinal top edge of said side rails; a bow clip attached to each leg end of the respective bows, said clips each having a projecting male member extending beyond and normal to the beveled face of said bow ends; a separate jamb strip for each of said side rails, each of said strips being provided with a series of integral stake pockets all set perpendicular to the top edge of the side rails and adapted to engage the respective parallel male members of said bow clips.

4. In a non-collapsible top structure for a vehicle body, a pair of main standards mounted upon opposite sides of the body,

- complementary side rails secured to the respective standards and extending forwardly therefrom over and substantially parallel to the top edge or trim line of the body, a separate jamb strip fastened to each of said rails, said strip extending below its respective rail to constitute a depending abutting face therefor and shaped to constitute a plurality of spaced offset stake pocket portions while the remaining intermediate spacing portions of the strip proper adjoin the side rail, a transverse bow bridging the side rails provided with a bow clip extending beyond each of the respective leg ends of the bow and engaging certain of said stake pockets, said clips being disposed contiguous to the respective side rails and encompassed by their respective offset pocket portions of the jamb strips, and sectional side panels mounted between the rails and the trim line of the body, the top sash edge of said panels being set against said abutting face of the jamb strip.
5. In a non-collapsible top structure for a vehicle top, a pair of main standards mounted upon opposite sides of the body, an angular bracket plate for each of said standards said plate having one of its legs secured to its respective standard, a separate jamb strip adapted to be supported by each of the other legs of the respective bracket plates, a side rail extending forwardly over the body and secured to and alongside each of said strips in an interposed relation with respect to the respective supporting legs, said strips being provided with a plurality of spaced parallel stake pockets offset from the adjacent side rails, and a transverse bow bridging the side rails having a bow clip attached to and extending beyond each of the respective leg ends of said bow and adapted to engage with certain of said stake pockets.
6. In a non-collapsible top structure for a vehicle top, a pair of main standards mounted upon opposite sides of the body, an angular bracket plate for each of said standards, said plate having one of its legs secured to its respective standard, a separate jamb strip adapted to be supported by each of the other legs of the respective bracket plates and extending forwardly over the body, a side rail comprising a plurality of similar sections secured along each of said strips in an interposed relation with respect to the respective supporting legs, said sections abutting end to end and being connected in alignment by means of said strip, an offset stake pocket for each of said strips, and a transverse bow having bow clips attached to the respective leg ends of said bow adapted to engage with said stake pockets.
- In testimony whereof, I have herewith set my hand this fifth day of February, 1924.

EARL H. WADSWORTH.
